UNITED STATES PATENT OFFICE.

GEORGE W. SHIEBLER, OF BROOKLYN, NEW YORK.

DESIGN FOR A HANDLE FOR SPOONS, &c.

SPECIFICATION forming part of Design No. 19,501, dated December 17, 1889.

Application filed November 4, 1889. Serial No. 329,229. Term of patent 7 years.

To all whom it may concern:

Be it known that I, GEORGE W. SHIEBLER, a citizen of the United States, residing at Brooklyn, in the county of Kings and State 5 of New York, have invented and produced a new and original Design for Handles of Spoons, Forks, &c., of which the following is a specification, reference being had to the accompanying drawings, forming part thereof.

10 Figure 1 is a representation of the design of the ornamentation of the handle on one side thereof, and Fig. 2 is a representation of the ornamentation on the other side of the handle.

The leading feature of the design on the 15 obverse side, Fig. 1, is a representation of the flower called "narcissus," with the stems, leaves, and flowers grouped as shown, and the leading feature of the design on the re-

verse side, Fig. 2, is a representation of a violet blossom, stems, buds, and a leaf, grouped 20 as shown.

What I claim is—

1. In a design for the handle of a fork or spoon, the design of the obverse side, substantially as represented. 25
2. In a design for the handle of a fork or spoon, the design of the reverse side, substantially as represented.
3. The design for a fork or spoon handle, substantially as herein shown and described. 30

Signed by me this 31st day of October, 1889.

GEO. W. SHIEBLER.
